UNITED STATES PATENT OFFICE.

CURTIS C. LILLIBRIDGE, OF HUTCHINSON, KANSAS.

OIL VAPORIZER AND BURNER.

1,295,775.

Specification of Letters Patent. Patented Feb. 25, 1919.

Application filed May 20, 1918. Serial No. 235,684.

To all whom it may concern:

Be it known that I, CURTIS C. LILLIBRIDGE, a citizen of the United States, residing at Hutchinson, in the county of Reno and State 5 of Kansas, have invented certain new and useful Improvements in Oil Vaporizers and Burners; and I do declare the following to be a full, clear, and exact description of the invention, such as will enable others 10 skilled in the art to which it appertains to make and use the same.

This invention relates to oil vaporizers and burners, and it relates more particularly to an improved oil burner attachment 15 for stoves and furnaces.

One of the objects of this invention is to provide a burner of this character which is applicable for attachment to practically any stove or furnace of ordinary construction;

20 Another object is to provide for preventing an excessive accumulation of oil in the stove, thereby minimizing the probability of explosion or other accident;

Another object is to shield the overflow 25 outlet against the entrance of drippings from the burner;

Another object is to provide for obtaining the minimum efficiency for vaporizing the oil prior to its entrance into the draft 30 of air to be mixed with the vapor preparatory to its combustion;

A further object is to obstruct the passage of oil while spreading the same in a thin layer so as to raise the temperature by 35 pressure as well as by the flame-producing heat;

A further object is to thoroughly and evenly spread the oil so as to produce an even flow of vapor around the burner; and—

40 Another object is to provide a burner which is composed of few, simple and comparatively inexpensive parts assembled without the use of fastening means, so that the device may be produced at a minimum 45 expense.

Other objects and advantages may become apparent to persons who read the following details of description in connection with the accompanying drawings, in which:

50 Figure 1 is a side elevation of a furnace with portions broken away so as to disclose the application of my improved burner therein;

Fig. 2 is an enlarged central vertical section view of the vaporizer and burner detached from the furnace;

Figs. 3, 4, 5 and 7 are perspective views illustrating the four component members or elements of my improved vaporizer and burner; and—

60 Fig. 6 is an enlarged detail sectional view taken along the line 6—6 of Fig. 5.

Referring to these drawings in detail, in which similar reference characters correspond with similar parts throughout the 65 several views, the furnace may be of any ordinary construction, and the controlling mechanism disclosed to the left of the break in the oil-pipes 9 and 10, being almost identical with the construction disclosed by my 70 Patent No. 1,234,194, dated October 16, 1917, will not be described in further detail than is necessary to disclose its relation to the burner which is generally designated (in Fig. 1) by the numeral 11.

75 Briefly described, the oil pipe 9 is the conduit through which the oil is introduced into the burner through an inlet opening 12 which communicates with a relatively thin and wide or disk-shaped passage 13 which has its outlet at 14 into an air passage which is indicated by the series of arrows designated by the numeral 15, this air passage extending substantially entirely around the upper margin of the burner. A drip-receiving channel 16 is formed about the lower 80 marginal portion of the burner, being disposed under the outlet 14, so that whatever vaporized oil passes through the outlet 14 drips into the channel 16 and is there accumulated for use in priming the burner and for adding vapor (to that which flows from the outlet 14) after the burner becomes thoroughly heated. The excess of oil 85 in the channel 16 beyond a predetermined amount, passes down through the pipe 10 into a container 17, and when a sufficient amount of oil has accumulated in the container or receptacle 17, its weight operates a valve controlling device 18 so as to control 90 the flow of oil substantially in the manner described in said prior patent. In the prior patent, however, the controlling devices 17 and 18 were disposed within the furnace, but this arrangement was found to 95 have certain disadvantages which are overcome by the present arrangement.

100 Referring to the specific construction of the burner disclosed in Figs. 2 to 7 inclusive, this burner consists of four castings 110 19, 20, 21 and 22 compactly fitted together to form a substantially disk-like structure,

being relatively wide in proportion to its height, thus enabling it to be disposed in the most advantageous position **within the** fire-pot of an ordinary stove or furnace.

5 Although the present disclosure is confined to a similar burner, it is contemplated to make certain of such burners oblong or of any convenient shape for application in fire-pots and fire-boxes other than circular ones. The roller element or casting 19 (see Figs. 2 and 5) constitute a ring-like body or annulus having a central opening 23 which constitutes the inlet of the air passage 15, an inner wall 24, an outer wall 25, and a 15 dam 26 having a vertical outlet 27 which communicates with the pipe 10, the channel 16 being formed between the walls 24 and 25. The top of the dam 26 is on a lower level than the top of the wall 24, so that 20 the contents of the channel 16 will overflow through the outlet 27 rather than over the wall 24.

The disk-like member or casting 20 has its inlet opening in communication with the 25 inlet pipe 9 which is secured thereto by a screw-threaded connection. The member 20 is formed with a crown or top surface whose general contour is convexed, but which has an annular groove 28 adjacent to its margin. This groove or depression acts to retard the oil in its flow through the passage 13 and to direct the oil circumferentially and thereby facilitate the most even distribution of the oil prior to its exit through 35 the outlet 14. In thus retarding the oil, it is given an extended opportunity to become vaporized. The member 20 is provided with legs or rests 29 which are provided with extensions 30, the latter being effective to centralize the member 20 with respect to the member 19, and when thus supported, as shown in Fig. 2, the outlet opening 14 is disposed over the channel 16 and over the oil outlet 27; and in order to prevent dripping of oil into the outlet 27, the shield or cover 22 is provided. This member 22 is shown separately in Fig. 7, and in Figs. 2 and 5 it is shown in its effective position over the dam 26 and outlet 27. In order that this cover 40 may have the maximum efficiency, its top is provided with a channel 31 which conveys the oil which drips thereon away from the opening 27. The upper part of the cover fits snugly between the walls 24 and 25, but 45 its supporting elements 31' are narrowed so as to provide oil passages 32 through which oil may pass and overflow through the opening 27. The disk-like upper member or casting 21 is formed with an arch or concaved lower surface 33 which is formed with an annular rib 34. The lower surface 33 conforms approximately to the shape of the upper surface of the member 20, and is spaced therefrom so as to provide the said 50 oil passage 13, the rib 34 combines with the

groove 28 for retarding and evenly distributing the oil. The member 21 is provided with radial extensions or rests 35 which are seated on the wall 19 and supported thereby. The margin is upwardly and outwardly inclined or flared, as indicated at 36, so as to direct the vapor and flame outward against the surface of the fire-pot in which it is enclosed.

70 The member 20 is provided with a depending flange 37 which prevents the oil from creeping inward toward the center of the burner and dripping through the air inlet.

75 Although I have described this embodiment of my invention very specifically, it is not intended to limit this invention to these exact details of construction and arrangement of parts, but I am entitled to make minor changes within the scope of the inventive idea disclosed in the foregoing description and following claims.

80 What I claim as my invention is:

1. In an oil vaporizer and burner, a member formed with a liquid-fuel receiving channel, a dam in said channel, and an overflow outlet in said dam; a fuel-distributing device above said member and in position to drop the fuel into the said channel; and a cover between said dam and fuel-distributing device, said cover and dam having a passage therebetween for allowing fuel to flow from said channel to said outlet.

85 2. An oil vaporizer and burner comprising a ring-like member, a lower disk-like member, and an upper disk-like member; said members being fitted together in superposed relation and forming a disk-like structure; said ring-like member having an air-inlet therethrough and having an oil-receiving channel around the air-inlet and under the periphery of the lower disk-like member; the upper disk-like member being spaced slightly above all parts of said lower disk-like member and thereby providing an unbroken disk-shaped oil-passage; the arrangement of said members providing a gaseous fluid outlet that communicates with said air-outlet and with said disk-shaped oil-passage; said lower disk-like member being provided with an oil-inlet that communicates with said disk-shaped oil-passage.

90 3. An oil vaporizer and burner comprising a ring-like member, a lower disk-like member, an upper disk-like member, and an oil-outlet cover; said ring-like member supporting the other said members and being formed with an oil-drip-channel, a dam in said channel, and an overflow outlet through said dam; said channel and overflow outlet being under the margin of said lower disk-like member; said cover being arranged over and spaced from said overflow outlet; said lower disk-like member having an oil inlet therethrough; said up- 95

per disk-like member combining with said ring-like member and lower disk-like member so as to form an oil passage and a gaseous fluid passage around and communicating with the oil passage.

4. An oil vaporizer and burner comprising a ring-like member, a lower disk-like member, and an upper disk-like member; said members being fitted together in superposed relation and forming a disk-like structure; said ring-like member having an air-inlet therethrough and having an oil-receiving channel around the air-inlet and under the periphery of the lower disk-like member; the upper disk-like member having a lower surface formed with a depending

annular rib; the lower disk-like member having an oil inlet through its center and being downwardly inclined therefrom to its periphery and being spaced at all its parts from said upper member and having an annular groove in registry with said rib so as to retard and to facilitate the even distribution of oil from said oil-inlet through the space between these members.

In testimony whereof I have hereunto set my hand.

CURTIS C. LILLIBRIDGE.
